UNITED STATES PATENT OFFICE.

JEAN LAFORÉT, OF LILLE, FRANCE.

AUTOMATIC COP-CHANGING MECHANISM WITH OSCILLATING LOADER MAGAZINE FOR LOOMS.

Application filed October 13, 1927, Serial No. 225,993, and in France October 19, 1926.

The present invention relates to the automatic vertical cop-changing mechanisms of the type in which the cop-magazine is oscillatably suspended and comprises rigid with 5 it its loader as described in the specification of my prior French Patent No. 613,684 of 30th March, 1926.

The object of the invention is to provide improvements with a view to controlling the 10 loader in such a way as to obtain its operation during the period represented by a quarter of a turn of forward stroke of the slay and of thus effecting the replacement of the exhausted cop by a full one in a gradual, 15 gentle and certain manner.

By means of these improvements, which together form an improved loader-controlling device in combination with the type of oscillating loader magazine for which it is 20 designed, an automatic vertical cop-changing apparatus is obtained which is simple and robust in construction, is certain and easy in operation and adjustment, is low in cost of manufacture and mounting and presents, 25 in addition, the great advantage of being easy to adapt for use upon the greater proportion of existing looms, both on looms with a horizontal picking motion and looms with a vertical picking motion since this adaptation necessitates no other alteration than the 30 production of an aperture in the shuttle-box for the passage of the exhausted cop expelled vertically.

The control device obtained from the improvements forming the subject of the present invention is hereinafter described and is illustrated diagrammatically in the accompanying drawings, in which:

Figure 1 shows a general arrangement of 40 the control mechanism of the oscillating loader magazine in side elevation.

Figures 2 and 3 show side elevations of modified forms adapted for use in construction arrangements special to certain looms.

Figure 4 is a side elevation of a modification of a constructional detail relating to the control of the correct setting of the shuttle in its box necessitated by certain loom arrangements.

In Figure 1 and with reference to the oscillating magazine proper of known type, 1 is the body of the loom, 2 a vertical support mounted upon the breast beam 3—4 the oscillating cop-magazine with a sharp bend 50 through about 90° at its lower part at 4'

so as to come above the shuttle-box until its end abuts against the rear face of the slay 5 when the latter approaches the middle point of its forward stroke, this magazine being for this purpose pivotally mounted 60 upon a horizontal rod 6 secured upon a horizontal arm 7 of the support 2 so that it can be swung towards the slay and returned by the latter.

8 is a lever keyed upon the operating bar 65 9 running along the length of the breast beam and oscillated under the action of the weft stop motion or of the feeler, as is well known, this lever 8 causing the changing mechanism to come into operation in the 70 manner indicated hereinafter.

10 is the loader block sliding along the lateral face of the vertical oscillating magazine 4 with its return springs 11 and the stop members 12 limiting the travel of the said 75 block 10.

13 is a lateral extension of the loader block 10 at the end of which is mounted the loader shoe 14 which is either fixed or pivotally mounted; in the latter case, the stops 15 80 limit its oscillation so as to make it possible to set the said shoe always in a common plane passing through the superposed cops 16 to be loaded and those 17 to be expelled, the automatic setting being obtained in an 85 adjustable manner by means of a balancing spring 18. The point of adjustment to a support 19 rigid with the magazine 4 can be varied on account of holes 20 in one of which can be hooked the said spring, the other end 90 of which is secured to the said shoe.

21 are the cop-separating points and 22 the blade connecting the magazine to the slay by the effect of its penetration into a hook 23 rigid with the slay at the moment 95 of loading.

24 is a picker-guide rod of looms with a horizontal pick and 25 the arm controlling the entry of the shuttle in the correct position into its box.

By means of the improvements made in the arrangement of the control of the changing of cops in the vertical loader magazine of the known type, the main parts of which have been described, above, the control of 100 the rearward movement of the oscillating magazine 4 towards the slay is no longer dependent upon levers, cams and pulling hooks controlling the loader; it is more simply obtained by means of a tension 105 110

spring 26 secured beyond the oscillating rod 6 and acting upon the magazine in order to make it swing towards the slay as soon as the said magazine is no longer hooked or 5 locked in the position of rest parallel to its vertical support 2 by means of a locking bolt 27 formed by the end of a bell crank lever 28 pivoted at 29, the oscillation of which, either for returning and holding the magazine 1 against its support 2 or for releasing it, is controlled by the oscillation of the arm 8 of the operating bar 9 of the weft stop motion by any intermediate members, for example by means of a link or preferably 15 by means of a flexible controlling cable 30 of the Bowden type, an adjustable shock-absorbing pad 31 being provided upon the support 2.

Again, according to the said improvements the control of the actuating mechanism of the loader of the oscillating magazine is no longer obtained by means of a pulling hook operating by means of a lever and a cam keyed upon the cam-shaft of the 20 loom but simply by the forward movement 25 itself of the slay, the effect of which makes it possible to benefit from the advantages of this method of control in combination with those of a changing mechanism in order to 30 obtain a gentle, gradual and certain change of the cop.

For this purpose, this mechanism modified with a view to its use in oscillating loaded-magazines of the type mentioned above, is 35 essentially composed of a rocking lever with two arms forming a U with an elastic pivotal connection, the lower branch of which pushed back by the slay approaching the middle point of its forward stroke causes 40 the advance of the upper branch which acts upon the loader.

This rocking lever is characterized by its construction and comprises oscillatably mounted upon a horizontal pivot 32 rigid with the breast beam, a branch 33 bent horizontal terminating at its base in a sleeve or socket 34 slipped with easy friction over the pivot 32 and at its upper end in an incline or bevel 35 adapted to act upon a roller 36 secured upon the lateral face of the loader block 10 sliding along the oscillating vertical magazine 4.

Upon the sleeve 34 is slipped with easy friction a second sleeve or socket 37 forming the base of a straight lever 38 extending the bent lever 33 the opposite lower end of which lever 38 is bent laterally at right angles at 39 and comprises an adjustable screw stop 40.

60 A projection 41 rigid with the sleeve 37 serves as stop for a regulating screw 42 mounted laterally upon the bent lever 33 so as to regulate the relative position of the two members thus pivotally connected together 65 which, when mounted, are elastically tied to-

gether by means of a bearing spring 43 of suitable strength formed by assembled elastic blades 44 in suitable number secured at 45 to the straight lever 38 and pressing upon a block 46 rigid with the bent lever 33.

At the lower part of the straight lever 38 is disposed laterally a rod 47 upon which is oscillatably mounted an arm 48 of which the end opposite the slay is bevelled so as to form an incline 49 upon which acts a 75 roller 50 mounted upon a support 51 rigid with the slay 5.

This arm 48 is normally maintained in a determined fixed position relatively to the straight lever 38 by means of a return spring 80 52 holding it against the stop 40 of the part 39 bent over it at right angles.

The opposite end of the arm 48 is formed in any suitable manner, as will be described hereinafter for purposes relating to the control of the correct setting of the shuttle in its box.

Thus formed, the separation of the arms 33 and 48 of the rocking lever, when adjusted by means of the screw 42, remains unvarying for determined efforts, but this separation can nevertheless be varied automatically by increasing the apertures by virtue of the elastic mounting of the pivotal point by the sleeves 34, 37 and the bearing spring 43 under abnormal forces produced by a defective operation or by any accidental external cause or further by reduction of the aperture by the lifting of the arm 48 when the shuttle is badly positioned.

For this purpose when the shuttle is not in the correct position it must of necessity occupy for changing the cop and in order to prevent the mechanism from operating under these defective conditions the control arm 25 oscillatably mounted upon a pivot rigid with the bed is constantly maintained in the control position by a spring 53. Upon this arm 25 is pivotally mounted at 54 a link 55 the opposite end of which comprises a roller 56 running in a notch 57 of suitable profile forming an incline and formed at the end of the arm 48 opposite to that comprising the bevel 49.

Upon the link 55 is formed a slideway 58 in which slides a pin or roller 59 secured laterally upon the vertical lever 38, the profile of the slideway 58 being such as to produce, when the control arm 25 is pushed back by the shuttle when in an incorrect position, the lowering of the link 55 and consequently by the roller 56 running upon the incline 57, the lifting of the arm 48, the incline or bevel 49 of which is thus moved out of contact with the roller 50 of the support 51 secured to the slay 5.

Upon the control arm 25 is secured a hook 60 provided for the purpose of holding and returning it by the pressure of the oscillating vertical magazine 4, when in its 120 125 130

position of rest, against the vertical support 2, the arm 48 with the incline 49 being, in this way, also held in the position of rest out of the path of the roller 50 of the slay 5 during the normal position of the loom.

In this improved arrangement, formed as described above, the mechanism operates in the following manner when a cop has to be changed.

10 Taking into consideration that the main members shown in full lines in Figure 1 are in the positions they occupy at the commencement of the operation it is easily understood that, under the action of the 15 arm 8 of the feeler or of the weft stop motion controlling the cable 30 of the oscillating lever 28 the magazine 4, having been disengaged has swung under the action of its spring 26 towards the slay with which 20 it comes into contact towards the middle of its forward stroke by means of its end 4' and by means of its connecting blade 22 and the hook 23.

At the same time as the push of the slay 25 5 compels the magazine and its loader to swing forwards the roller 50, rigid with the slay, rolls gradually by contact upon the incline 49 of the arm 48 which, as it cannot yield on account of its stop mounting 40 upon the vertical lever 38 produces, as shown in dot and dash lines, the progressive oscillation of the said lever 38 and consequently the gradual advance of the bent 30 lever 33, the incline 35 of which, by pressing in a gradual manner upon the roller 36 of the loader block 10, produces the gradual 35 descent of the latter and consequently that of the shoe 14 upon the full cop 16, which is thus made to replace gradually and surely 40 without impact, the exhausted cop 17 by expelling it in a vertical direction the operation being terminated at the exact moment when the slay reaches the end of its forward travel.

45 When the slay recoils the oscillating magazine 4, which had been brought into its position of rest parallel to the vertical support 2 again oscillates under the action of its tension spring 26 accompanying the slay 5 until about the middle point of its backward travel, at which moment the separation takes place the disengagement of the separating points 21 of the cops end of the connecting blade 22 taking place without 50 shock. By virtue of this accompanied movement of the magazine the contact of the loader shoe 14 upon the new cop is prolonged, thus ensuring loading in an absolutely complete manner in view of the fact 55 that the duration of this contact is thus effected during the period which lasts approximately for the last half of the forward stroke of the slay and the first half of its backward travel.

60 Moreover, by virtue again of this accom-

panied movement of the magazine when the slay recoils in combination with the contact by rolling of the rollers 36, 50 upon the inclines 35, 49 of the rocking lever the operations are effected gradually without impact, without sound and also in loading the operations are effected gradually without impact, without sound on account of this rolling contact of the rollers on the inclines of the said swinging lever.

The return of the oscillating magazine, when it is abandoned by the slay 5 completing its forward travel into its position of rest parallel to the vertical support 2 against its stop pad 31 is effected by the control 30 70 80 acting upon the lever 28 provided with the locking bolt 27; the effect of this is to reduce, by means of the hook 60 the recoil of the control arm 21 which through the medium of the link 55 and of its roller 56 upon the 85 incline 5 of which brings the arm 48 into the inoperative position, as shown in dotted lines.

In the case when, at the moment of changing, the shuttle is not in the correct position 90 in its box, the detector arm 25 by advancing at the same time as the magazine swings towards the slay, meets the shuttle and on this account is pushed back, the effect of which is to cause, by means of the link 55 95 slotted at 58 and its roller 56 acting upon the incline 57, the arm 48 to lift above the track of roller 50 of the slay 5.

This improved automatic cop changing device according to the invention may, on 100 account of its very construction, not be applicable to all types of looms, on account of their special construction.

In order to remove this disadvantage modifications of the loader controlling mechanism, by swinging lever with elastic pivotal mounting, are provided, based upon the same principle of construction and illustrated in Figs. 2 and 3.

In the first form the **U** is formed by two 110 arms 61 and 62 with inclines adapted to come into contact with the roller of the slay and that of the loader block.

These two arms 61 and 62 are pivotally mounted at fixed points 63 and 64 upon the 115 support 2 and made rigid with each other by means of an elastic cross stay pivotally mounted at its end at 65 and formed by two parts 66 and 67 sliding one in the other or one upon the other, with an elastic connection by means of a tension spring 68 of strength chosen so that it will only yield and permit the separation of the arm 61 and 62 in the event of an abnormal effort of resistance in changing the cop, the effect of which 120 is to prevent defects or accidents.

With this device of modified construction, the movement for changing the cop is effected under the same conditions according to the principle of compression envisaged.

For the case of a bad stoppage of the shuttle in the box, an arm 69 actuated by the control arm 25 makes the whole arrangement of the two arms 61 and 62 rise above the rollers 36 and 50.

In the second constructional modification the two arms 70 and 71 are arranged in the form of an angle piece with a double elastic pivotal mounting similar to that of the device shown in Fig. 1. The upper branch 10 70 operates in the ordinary way, by co-operating with the roller 36 of the loader block, but the vertical arm 71 no longer cooperates with the roller 50 of the slay 5, but 15 directly with the lever 8 keyed upon the operating bar 9 of the weft stop motion or of the feeler, by means of a roller 72 acting upon its bevel in order to cause the upper branch 70 to be lowered, a notch or groove 20 73 provided upon the vertical arm 71, receiving the roller 72 and holding it fixed when the arm 70 comes into contact with its bevel 35 upon the roller 36 of the loaded block which it causes to operate.

In the case of an abnormal effort, the elastic pivotal joint enters into action by preventing all possible inconveniences, the arrangement taking up again its normal position after the change as a result of the 30 lowering of the arm 8.

Finally, still on account of certain types of loom construction, the actuation of the control arm 25 for preventing changes of cops from being effected in the case of bad positioning of the shuttle in its box, must be modified.

For this purpose, and by way of modification, as shown in Fig. 4, the control arm 25 is connected by its link 55 to a small lever 74 40 oscillating about a fixed point 75 and comprising the roller 56 at its lower end, rolling upon the incline 57 of the arm 48 of the swinging lever with elastic pivotal connection already described.

What I claim is:

1. A control mechanism of the loader, in an automatic vertical cop changing mechanism comprising a vertical cop magazine oscillatably suspended adjacent the path of movement of a slay of a loom, resilient means tending to move said magazine in one direction, a loader carried by said magazine, releasable locking means for holding the magazine in an inoperative position against the tension of said spring, means to release said locking means operable by the bar of the weft stop mechanism of the loom to permit said magazine to swing into the path of movement of the slay of the loom, a loader mechanism carried by said magazine, said loader mechanism comprising a reciprocating member, a roller mounted on said member, means operable by the movement of said slay to move said reciprocating member comprising a member pivotally mounted

to be swung by the movement of the slay to a position to engage the roller on said reciprocating member, a cam surface on said pivoted member, whereby the reciprocating member is progressively moved to eject a 70 cop.

2. In a control mechanism as claimed in claim 1 wherein the means for operating the reciprocating member of the loader comprises a lever formed in two parts, an upper 75 bent part with a bevelled end forming an incline acting gradually upon said roller mounted on said loader, a shaft for said part, a vertical part mounted on said shaft, the lower end of said vertical part comprising an angularly extending portion, an adjustment screw on said angular portion, an elastic pivotal connection arrangement holding together the two parts comprising a pressure leaf spring secured upon the 80 vertical part and pressing against the bent part, means to adjust the relative position of the two parts against the tension of the spring, a second lever pivoted to the end of the vertical part of said first mentioned 85 lever, resilient means elastically holding said second lever against the stop screw of the angular part, said second lever having a bevel forming an incline upon which the slay of the loom acts to cam said second named 95 lever to move the first mentioned lever to operative position with relation to the loader.

3. In a control mechanism as claimed in claim 1 and in combination therewith of means to render the loader operating mechanism 100 inoperative in case the shuttle is not in proper position to receive the cop.

4. In a control mechanism as claimed in claim 1 wherein the means for operating the reciprocating member of the loader comprises a lever formed in two parts, an upper 105 bent part with a bevelled end forming an incline acting gradually upon said roller mounted on said loader, a shaft for said part, a vertical part mounted on said shaft, the lower end of said vertical part comprising an angularly extending portion, an adjustment screw on said angular portion, an elastic pivotal connection arrangement holding together the two parts comprising a 110 pressure leaf spring secured upon the vertical part and pressing against the bent part, means to adjust the relative position of the two parts against the tension of the spring, a second lever pivoted to the end of the vertical part of said first mentioned lever, resilient means elastically holding said second lever against the stop screw of the angular part, said second lever having a bevel forming an incline upon which the slay 115 of the loom acts to cam said second named lever to move the first mentioned lever to operative position with relation to the loader, and in combination therewith of means to render the loader mechanism 120 125 130

inoperative in case the shuttle is not in proper position to receive the top comprising an extension on said second lever provided with a cam surface and means for pivoting said second lever to a position out of operative engagement with the slay comprising a movable link having a roller engaging said cam surface on said second lever and means to operate said link in accordance with the position of said shuttle.

5. In a control mechanism as claimed in claim 1 wherein said means for operating the reciprocating member of said looper com-

prises two members pivoted to move in a vertical plane, a cross member connecting 15 said two parts, one of said members having a beveled end to engage the roller on the looper, the other of said members having a beveled end to engage the slay of the loom in its movement, said cross member consisting of two relatively sliding parts, a 20 spring tending to return said parts to a normal relative position.

In testimony whereof I affix my signature.

JEAN LAFORÉT.
